UNITED STATES PATENT OFFICE

MAXWELL C. MAXWELL, OF STAMFORD, CONNECTICUT, ASSIGNOR TO THE YALE & TOWNE MANUFACTURING COMPANY, OF STAMFORD, CONNECTICUT

PADLOCK

Application filed May 4, 1929. Serial No. 360,498.

This invention relates to padlocks, more especially padlocks whose casings are made of sheet metal and are designed to be drawn into the particular configuration desired. 5 The object of this invention is to design a padlock of this latter type wherein the form of the padlock casing will lend itself easily to sheet metal fabrication, and where the form of the casing may be utilized to 10 maintain the locking mechanism of the padlock in proper position.

For a detailed description of my invention, I refer to the drawing, wherein Fig. 1 is an elevation of my padlock and Fig. 2 is a 15 section of the same showing the locking mechanism in position. Fig. 3 is a top and front view of the plug tube which is adapted to hold the locking plug of the padlock in position. Fig. 4 is a bottom view of the padlock showing the position of the plug in relation to the casing. Fig. 5 is a section along the line 5—5 of Fig. 2, showing the locking bolt in its relation to the shackle. Fig. 6 is a front and side view of the locking bolt.

25 Fig. 7 is a top, side, and bottom view of the shank on which the bolt is mounted. Fig. 8 is an end, side, and front view of the locking plug. Fig. 9 is a side and front view of the tube adapted to contain the long leg of the 30 padlock shackle. Fig. 10 is a top and side view of a separator adapted to hold two of padlock plates in separated position. Fig. 11 is a side and top view of the top plate of the padlock. Fig. 12 is a side and top 35 view of the upper inside plate of the padlock. Fig. 13 is a side and top view of the second inside plate, while Fig. 14 shows similar views of the bottom plate. Fig. 15 is a side and end view of the plug retaining slide.

40 Referring more particularly to the drawing, it will be noted that the bottom 10 and sides 11 of my padlock casing are formed of one piece of sheet metal, suitably drawn into the particular configuration shown. The separator plates 13 and 14 shown in Figs. 13 and 14, are adapted to be forced into their positions on the step portions 15 on the inside of the padlock. These separator plates are utilized to support the tubes 16 and 17 shown 45 in Figs. 3 and 9, these tubes acting to main-

tain the shackle and the locking plug in their respective positions.

The tube 16 has the ears 18 which fit into the slots 19 and 20 of the plate 13 to hold the tube in position. The shackle tube 17 has a 55 long leg 21, which is adapted to rest on the bottom end 10 of the casing. The shoulder portion 22 of the tube is adapted to rest on the separator plate 14, while the top edge 23 is adapted to support a still further separator 60 plate 12. The tube 17 is cut-away at the point 24 and the shackle retaining member 25 shown in Fig. 15 is adapted to enter into this cut-away portion to prevent the shackle from 65 being ejected too far by its ejecting spring 26.

In order to more fully maintain the plate 13 in its proper position, I utilize a plate separator 27 shown in Fig. 10. This member 27 has a projecting portion 28 which is adapted to fit within the cutaway section 29, while its 70 upper edge 30 is adapted to support the top plate 12. As described, the other end of this plate rests on the upper edge 23 of the shackle tube 17.

The top plate 31 of the padlock casing has 75 bent over edges 32 which are adapted to be sprung into the padlock casing as shown in Fig. 2 and to be thus securely held in the designated position. If desired, this top plate may later be welded or be further secured in any suitable manner.

80 In order to lock the padlock shackle 32 securely within the casing whenever it is desired, I have provided the same with locking sections at points 33 and 34. The rotary 85 bolt 35 is pierced at the point 36 in order that it may be securely mounted on the portion 37 of the bolt shank 38. This bolt shank 38 is equipped with a bearing portion 39 which rests within the bearing hole 40 of the 90 separator plate 12. The bottom portion of the bolt shank 38 is equipped with the up-standing lugs 41 with which the plug cam 42 is adapted to cooperate.

95 As shown in Fig. 8, the plug 43 carrying the cam 42 may be of any usual type, the sliding tumbler type being used in this particular case. It should be understood, however, that it is within the scope of this invention to use any type of locking mechanism, 100

a warded mechanism being suitable in some cases. This plug 43 is cut away at 44 to contain a spring retaining member 45. Thus, whenever, it is desired to assemble this plug 5 in its proper position in the lock casing, it is merely necessary to hold the spring member 45 within the cut-away portion 44, and insert the plug into the tube 16. It will be readily understood that when the spring 45 reaches 10 the bulging portion 46 of this tube it will spring into the same and will maintain the plug into its proper position thereafter.

The bolt 35 is normally urged into locking position by the coiled spring 47 which 15 has one end resting in the hole 48 and has its other end bearing against the side of the bolt at the point 49. This spring will normally urge the bolt into locking position as limited by studs 50 on plate 12. The cam 20 42 of the plug 43 through its contact with the lugs 41 of the bolt shank 38 will be adapted to actuate the bolt against the pressure of this spring and into unlocking position. However, because of the lost motion existing 25 between the lugs 41 and the cam 42, it will be possible to retract the bolt and then return the cylinder to its locked position to withdraw the key without disturbing the unlocked condition of the padlock.

30 The operation of my lock is as follows: When a key is inserted into the plug 43, it will act to set the tumblers or will cooperate with the warded mechanism so that the plug may be rotated. It will then actuate the bolt shank 38, by means of the lugs 41 and the plug cam 42, to rotate the bolt 35 against the action of the spring 47. This will remove the bolt from the shackle locking portions 33 and 34 so that the ejecting spring 26 will be 35 capable of shooting the same into its upward unlocking position, the extent of this action being limited by the retaining member 25. The plug 43 will then be capable of being rotated back to its locking position due to 40 the lost motion existing between the studs 41 and the cam 42. The bolt 35 will remain in its unlocked position, being held in that position by the shackle 32 until such time as that shackle is depressed and the bolt is forced by its spring into the locking portions 45 33 and 34.

50 While I have shown one modification of my invention, it should be understood that I do not wish to be limited to the same, since other adaptations within the scope of the appended claims may suggest themselves to one skilled in the art.

I claim:

55 1. In a padlock, a sheet metal casing having a configuration comprising a series of graduated internal steps, a series of plates carried by said internal steps, and tubes maintained in position by said plates for supporting the shackle and the key controlled 60 mechanism of said padlock.

2. In a padlock, a sheet metal casing having integral sides and bottom, said sides having a configuration comprising a series of internal graduated steps, a locking cylinder in said padlock, and a series of plates resting 70 on said graduated steps and adapted to support said cylinder.

3. In a padlock, a sheet metal casing having integral sides and bottom, said sides having a configuration comprising a series of internal graduated steps, a tube in said padlock adapted to contain a locking plug, and a series of lateral plates supported by said internal steps and adapted to support said locking tube. 75

4. In a padlock, a sheet metal casing having integral sides and bottom, said sides having a configuration comprising a series of internal graduated steps, a locking tube in said padlock, a shackle containing tube in said padlock, and a series of plates adapted to be supported by said graduated steps and perforated for the support of said locking and shackle tubes. 80

5. In a padlock, a sheet metal casing having integral sides and bottom, said sides having a configuration comprising a series of internal graduated steps, a series of plates adapted to be supported by said internal steps, perforations in said plates and a lock 90 containing tube adapted to rest in said perforations to be supported by said plates. 95

6. In a padlock, a sheet metal casing having integral sides of a configuration comprising a series of internal graduated steps running completely about the internal periphery of the casing, a series of plates adapted to rest on said steps, and held in position thereby, and locking mechanism supported by said plates and movable relatively thereto for controlling the shackle of said padlock. 100 105

Signed at Stamford in the county of Fairfield and State of Connecticut this first day of May A. D. 1929.
